UNITED STATES PATENT OFFICE.

JOHN E. ARMSTRONG, OF SANTA CRUZ, CALIFORNIA.

VEHICLE.

SPECIFICATION forming part of Letters Patent No. 766,485, dated August 2, 1904.

Application filed November 24, 1903. Serial No. 182,444. (No model.)

To all whom it may concern:

Be it known that I, JOHN E. ARMSTRONG, a citizen of the United States, residing at Santa Cruz, in the county of Santa Cruz and State 5 of California, have invented new and useful Improvements in Vehicles, of which the following is a specification.

My invention relates to vehicle construction, and especially to the mounting or suspension 10 of the body of the vehicle upon springs by which it is supported from the axles or running-gear.

It consists in a novel means for suspending the body by swinging links and hangers and 15 in the connection therewith of springs which are operated in unison to depress all parts of the body simultaneously without reference to the part upon which the load may be placed.

It also comprises details of construction 20 which will be more fully explained by reference to the accompanying drawings, in which—

Figure 1 is a side view of the body of a vehicle, showing my device. Fig. 2 is a bottom view of same.

25 In the ordinary construction of carriages and in mounting them upon springs the point upon which the weight is placed usually determines that that portion of the vehicle will be depressed more than any other portion.

30 It is the object of my invention to provide such a device and means for supporting the body with relation to the running-gear that the weight placed upon any point will depress all portions of the body substantially the same.

35 As shown in the drawings, A represents the wheel-axles of the vehicle.

2 represents bolsters, and 3 represents the carriage-body, which may be of the usual or any suitable construction. In order to prop- 40 erly suspend this body from the bolsters and to give it the necessary elasticity and freedom of movement, I have shown the following de- vices.

4 represents crank-arms formed upon shafts 45 which are journaled to the bolsters in any suitable manner.

5 represents shafts extending across and turnable in boxes or supports on the carriage-body and near each end thereof. These shafts 50 are bent or cranked, as shown at 6, and are

connected with the pins of the cranks 4, as shown. Conveniently disposed upon the shafts 5 are drums or equivalent projections, as at 7. These drums are so fixed as to be turnable with the shafts 5.

55

8 represents springs, here shown as being coiled about the shafts 5, having one end of each extended and fixed to the vehicle-body 3 and the other end of the coil attached to the drum or its equivalent 7, so that the body is 60 supported by the elasticity of these springs, and any depression of the body will by reason of the connection between the cranks 4 and 6 act to turn the shafts 5, and thus coil the springs 8 about the shafts. The tension of the 65 springs will be increased by this coiling, and being properly proportioned for the weight they are designed to carry they will provide an elastic and easily-movable support for the carriage-body. In order to operate these 70 springs and supports in unison, I have shown a connection between the drums or the equivalent rocker-arms or part which consists of cords or rods, as at 9. These may be preferably made, as shown, crossing each other, so that 75 one connects at the top of one of the drums and at the bottom of the other, and if two of these connections are used the other one will cross the first one diagonally, so that one end connects with the top of the drum or arm op- 80 posite to the bottom connection of the other. Thus any movement to depress one end, corner, or side of the body will act to turn the connecting-cranks 4 and 6, and the crank 6, acting through its shaft 5, turns the drum 7, 85 thus compressing the spring 8, and this spring and the rotation of the drum 7 by reason of this depression will act, through the connec- tions 9, to simultaneously and synchronously rotate the other drum, thus acting through its 90 spring to turn the shaft 5 and crank 6, so that both ends of the body are equally de- pressed without regard to what point the pressure may be applied to.

Having thus described my invention, what 95 I claim, and desire to secure by Letters Patent, is—

1. The combination with the running-gear of a vehicle and the body thereof of crank- 100 shafts, one pair journaled upon the bolsters

and the other pair near the ends of the body said crank-shafts journaled in substantially the same horizontal plane and having their outer ends converging downwardly and mov- 5 ably connected, winding-drums fixed to the shafts journaled upon the body-springs coiled around the shaft having one end secured to the body and the other to the drum, and connections between the two drums and attached 10 respectively to the upper and lower parts thereof whereby both are turnable in unison when pressure is applied to either end of the vehicle-body.

2. A vehicle-body or the like having shafts 15 journaled near the ends, said shafts having crank-arms extended outwardly on each side of the body of the platform, links to which the ends of said cranks are connected, said

crank-arms and links diverging upwardly from their point of connection, drums secured 20 to the crank-shafts beneath the body, coiled springs surrounding the shafts having one end of each connected with the platform and the other with the drums, and connections ex- 25 tends diagonally across each other from the top of one drum to the bottom of the other whereby the torsion of the springs and the depression of all parts of the vehicle-body are substantially simultaneous.

In testimony whereof I have hereunto set 30 my hand in presence of two subscribing witnesses.

JOHN E. ARMSTRONG.
